UNITED STATES PATENT OFFICE.

CHRISTIAN N. BERGMANN, OF PITTSBURGH, PENNSYLVANIA, ASSIGNOR TO BERGMANN PACKAGING MACHINE COMPANY, OF PITTSBURGH, PENNSYLVANIA, A CORPORATION OF DELAWARE.

UNIT-MEASURING MACHINE.

Application filed December 14, 1923. Serial No. 680,633.

My invention refers to improvements in machines for measuring units of mobile material, as ice cream, and in separating such measured units from a mass and depositing them separately into containers. Also, to an improved method of separating such unitary portion from the mass without increasing its density or reducing its content.

The machine for such purpose is of that 10 class disclosed in my pending application Serial No. 613,235, filed January 17, 1923, and the present invention involves improvements with respect to the construction of the rotatable cylinder containing the unit 15 cavities; the casing therefor; means for automatically controlling the operation of the cylinder with respect to the receptacle container, and various other features of construction and operation, as shall be more 20 fully hereinafter described.

Generally stated, the machine is adapted to deposit unitary amounts of ice cream or other suitable material into cups, receptacles, or containers, for the purpose of vending 25 or storing the same in package form, in a simple, economical, efficient and expeditious manner.

The invention has in view to use a continuous series of carrying trays, arranged to 30 hold the containers and to successively present them in proper position to be filled and sealed, a supporting trackway therefor, and means for advancing the tray and containers successively through the machine for filling 35 and closing. Also, means for delivering a measured amount of material into each receptacle, controlled and operated by the tray so as to ensure proper positioning of the containers throughout the operation.

The machine is so constructed and arranged that one tray after another, filled with empty receptacles, will pass through the machine, and the receptacles will be filled and closed, the tray then passing outwardly at the other end, where it may be removed with its filled contents, ready for use.

In the drawings illustrating one preferred embodiment of the invention,

Fig. 1 is a view of the machine in side elevation;

Fig. 2 is an enlarged longitudinal vertical section in the line II—II of Fig. 1;

Figs. 3 and 4 are sectional detail views on

the line III—III of Fig. 2, showing the 55 automatic controlling mechanism for the rotatable unit cylinder, dependent on the receptacle tray;

Fig. 5 is a perspective detail view of the 60 pawl arresting arm;

Fig. 6 is a horizontal sectional view on the line VI—VI of Fig. 2;

Figure 7 is a cross section on the line 65 VII—VII of Fig. 2;

Fig. 8 is a cross section on the line 70 VIII—VIII of Fig. 2;

Fig. 9 is an enlarged sectional detail view of the pawl actuating mechanism, similar to Fig. 2, on the line IX—IX of Fig. 4, showing the pawl retracted as when there are 75 no receptacles in receiving position;

Fig. 10, is a face view of the segmental gear retracted; and

Fig. 11 is a detail view showing a modified construction for driving the actuating 75 segmental gear; and

Fig. 12 is a detail sectional view, enlarged, showing discharge of a formed unit

The particular objects in view in the present invention are to provide automatic 80 mechanism for accurately and positively rotating the intermittently operable cylinder which measures, separates, and delivers the units into the receiving cups or receptacles, in conformity with the intermittent advancing movement of said receptacles, and to effect unitary measurement, separation and delivery without compression; also to provide, in such construction, for easy and convenient removability of the cylinder for 85 cleaning, etc., to provide for an air circulation through such cylinder to effect temperature regulation, and means to prevent creepage or spreading of the material by a particular formation of the outlet apertures of 90 the cylinder casing.

Referring to the drawings illustrating the invention, the machine as a whole is generally rectangular in form, having an extended horizontal frame 2 at each end of 100 and beyond a main supporting pedestal 3. Extending throughout the length of the frame, from one end to the other, and along each inner side, are suitable trackways 4, of flanged or angle form as shown, for sliding support of the cup or container carrying frame or tray 5, shown in dotted lines in Fig. 2. Said tray is adapted to be advanced

intermittently along such trackway by the reciprocable bar 6, and engagement thereby of the pawl on the under side of the cup frame, as shown and described in the prior 5 application above referred to.

The cup carrier, as therein shown, is provided with suitable receiving cavities extending crosswise in rows, spaced apart longitudinally of the holder a distance 10 equalling each forward intermittent movement, whereby to bring each successive transverse row of receptacles underneath the unit measuring mechanism. The latter, which is of the same general construction 15 and operation as that shown and described in my said prior application, and also in application Serial No. 579,125, comprises a rotary barrel or cylinder 9, mounted within a cylindrical casing 10 below the delivery 20 portion 11 of main hopper 12. Delivery cavities 11 are divided by transverse tapered partitions 13, whereby to more easily direct the contents of the hopper into each transverse unit forming cavity 14 of barrel 9. 25 Within said barrel and in each cavity 14 thereof is the slidably mounted reciprocable valve or plunger bottom 15. As shown, there are a series of such cavities and plungers, transversely of the machine and lengthwise of the barrel, each operating independently of the other, but together in discharging corresponding series of formed units into the several receptacles *a* of carrying tray 5. Each plunger or bottom 15 is capable of alternating gravitating movement 30 across the middle width of its cavity at each half revolution of the barrel, and is limited against further gravitating movement by the inwardly projecting narrow annular lip 35 16 of casing 10, and also of extracting and retaining sufficient ice cream composing the next succeeding measured unit thereabove, ready to be sheared off from the main supply mass, upon the next half rotation of the 40 barrel 9.

As shown, the bottoms 15 are of comparatively large size, occupying about one-half of the transverse length of each cavity, more or less, according to conditions. The 45 main condition controlling the relative size of the plungers and cavities is that the plungers shall have sufficient weight to positively effect the suction and discharge operation on the ice cream units, by gravitation. 50 As will be obvious, the quantity of material to be filled into the containers is controlled by the size of the plungers, and the consistency of the material being charged into the containers controls the weight of the 55 plungers. The plungers are slidably mounted therein and maintained in alinement by a tongue and groove guiding key or spline 58, as shown. Such guiding mechanism is necessary in order to maintain the several 60 plungers in proper alinement, their ends be-

ing curved conformably to the contour or circumference of the rotatable barrel 9 in which they are mounted.

For the purpose of avoiding accumulation of ice cream around the lower edge of the outlet cavity of each sectional unit forming space, the casing is provided with an annular tapered lip 17 extending downwardly around the space immediately below shoulder 16, terminating in a thin knife edge, from which any adhering particles of ice cream will readily drop off, and avoid accumulation, as the several units are discharged. As shown, the casing 10 is annularly recessed adjacent to and immediately above the lip 17, so that any spreading of melted cream is prevented by such surrounding channel. The several plungers 15, by reason of their extended length, and being of solid metal, are of substantial size and considerable weight. By reason of the nature of the substance used in the machine, containing a proportion of butter fat, the walls of the cavities and these bottoms are continuously lubricated, and therefore slide 85 with great ease and an absence of retarding friction.

In operation, as the cylinder 9 is intermittently rotated one-half revolution each time, the several plungers 15 are carried around towards the top and under the delivery opening of each cavity 11. Due to their practically air tight mounting within the casing, they will not commence to slide or fall downwardly until the cavity 14 communicates with the hopper supply above and the outlet opening below. When the vertical position has been reached, and with the several cavities 14 in full register above and below, the cylinder 9 then comes to rest. 90 Upon such openings being established, gravitation of the plungers 15 will gradually effect downward movement of portions of the contents of the main hopper by suction, assisted by the weight of the superimposed 95 contents, so as to fill each cavity above the plunger 15 as it falls toward the bottom of the opening (Fig. 2). At the same time, the previously measured and sheared off units are ejected (Fig. 12) into the registering receptacles *a* which, when filled, are then moved forwardly in the tray 5 one space by bar 6.

Due to the suction effect of plungers 15 and the substantial vacuum condition existing in each of the several cavities 14, there is a degree of tension exerted, tending to somewhat expand the ice cream, or at least filling the cavities without any tendency to compress or solidify the substance. Likewise, in ejecting the unit, it falls into the cup by gravity, at the same time maintaining suction on the plunger and assisting its action. Such suction operation is a feature of considerable advantage in assisting in 130

maintaining, in the filled receptacles, the full one hundred percent of the original batch of main reservoir 12, without diminution of bulk.

6 Cylinder 9 is mounted in its casing 10 in such a manner as to be easily inserted and withdrawn therethrough, and at the same time concentrically mounted and rotated, without friction. For such purpose, it is 10 provided with centrally arranged terminal hubs 18, 19, respectively, hub 18 having a centrally bored cavity for engagement with the stud 20 of driving shaft 21. Said shaft also has a pair of oppositely located keys 22 15 adapted to register with corresponding sockets 23 of hub 18, so that, when barrel 9 is inserted from the opposite end, it must necessarily register properly, dependent upon the proper positioning of shaft 21, so 20 as to ensure vertical positioning and registering location of the several cavities 14.

At its other end, hub 19 of barrel 9 is provided with an extended stud 24, secured in the hub and extending into the central 25 hub bearing 25 of supporting ring 26. Said ring is secured upon the outer end 27 of casing 10, by a flanged extension of the ring, which in turn is engaged by the ring nut 28 screwed upon the threaded terminal 27, 30 as shown. By unscrewing ring nut 28 and removing the supporting ring 26, the barrel may be drawn outwardly for cleaning or repair, care being taken to avoid dropping the several plungers as the barrel is withdrawn.

At its other end, shaft 21 is rotatably mounted in a similar supporting ring 29, secured on the end of casing 10, as shown at 30, and rings 26 and 29 are each provided 40 with air circulation openings, 31 providing for free circulation of warm air currents through the entire length of the barrel when desired. For such purpose the barrel is cored out, as at C, Fig. 6. The purpose and advantage of such currents is to maintain the 45 temperature of the working parts at a degree sufficiently high to be always warmer than the ice cream itself. By so keeping the temperature of the machine higher, I prevent any tendency of the ice cream to stick or freeze to the working parts, thereby avoiding any binding or tendency to clog the machine. The opposite ends of casing 10, as shown, are mounted in the upper portions of brackets 32, of each side frame of the machine, as will be readily understood.

The several operative portions of the machine are maintained in driving connection with a motor M through a suitable drive 50 shaft and gearing, transmitting motion to a series of transverse shafts which extend across the machine and are mounted in the side portions thereof, as in Fig. 1.

For the purpose of intermittently actuating 55 barrel 9 from one of such shafts, I

utilize a reciprocable segment 33 journalled on the end of one of such shafts 34 and actuated by a pitman 35 from crank disk 36 on the end of another such shaft 37. Pitman 35 transmits the proper throw to segment 70 33 continuously in a forward and back direction as crank disk 36 revolves, the proper timing and relationship to the other working parts of the machine, by suitable gearing, not necessarily herein described.

75 The teeth of segment 33 are in intermeshing engagement with the teeth of gear 38 which is so proportioned as to receive a one-half revolution in alternating reverse directions, for each reciprocation of segment 80 gear 33. It is designed that such alternating rotation of gear 38 shall impart a series of successive half rotations to barrel 9, all in the same direction, with an intervening rest period on reverse movement of segment 85 33. Such rest period is incident to filling, formation and discharge of the unitary measured sections to be delivered to the receptacles a.

To effect such purpose, shaft 21 is provided with a ratchet wheel 39 having a ratchet shoulder 40 at each opposite side, adapted to be engaged by spring pressed pawl 41 of shrouded wheel 42.

Gear wheel 38 and wheel 42 are fixedly 95 connected by key or screw 43 so as to operate together, or they may be made integral as one piece, if desired. An advantage in making them separate and so connecting them is that it facilitates the cutting of the teeth of gear 38 as a separate unit. However, both are freely rotatable together upon the neck 44 of stud shaft 21, while ratchet wheel 39 is keyed to the middle portion of said shaft, as at 45. As thus constructed, alternating 100 rotation of wheel 42 will effect pushing engagement of pawl 41 with shoulder 40 and a resulting half rotation of barrel 9, for each reciprocation of wheel 42, which then rotates freely and idly in the reverse direction 105 for similar engagement with the opposite shoulder 40. In such movement, the pawl 41 engages shoulder 40 at the bottom, moving it around to the top through one complete half rotation corresponding to the 110 active period and reversing to the original bottom position on reverse movement of segment 33 during the rest period.

115 For the purpose of rendering such mechanism inoperative when there are no receptacles in receiving position below the unit forming mechanism, and of, conversely, effecting such operation when the tray 5 with its receptacles comes into such receiving position, I have provided a controlling device for the pawl 41, subject to actuation by the tray upon entering the machine and upon passing beyond such device. This consists of an arm 46 mounted on rock shaft 47 having at its other end a lever arm 48 pro-

vided with a terminal roller 49 located in the path of the tray 5. Arm 46 is provided with an elongated clearance opening 50 surrounding shaft 21 and has at one side a 5 curved cam or fender extension 51.

The outer face 52 of fender 51 is curved substantially concentrically with the shaft center and is adapted to be thrown into the path of pawl 41 when the machine is empty, 10 or when the tray 5 has passed beyond the roller 49, as in Fig. 4. Under such conditions, the gravitating action of lever arm 48 and its roller and the weight of arm 46, throw said arm downwardly, bringing face 15 52 of fender 51 into the path of the pawl 41, so that it is thus maintained out of operative range of ratchet shoulder 40. Pawl 41 is sufficiently wide to extend beyond the ratchet wheel and into the path of fender 51, as 20 shown.

Upon a tray entering the machine, it will ride under roller 49, as in Fig. 3, thrusting it upwardly and raising fender 51 out of the path of pawl 41, so that the pawl will act to 25 half rotate wheel 39 and cylinder 9. By this means, the mechanism is inoperative to effect rotation of the unit measuring mechanism until the tray has entered the machine, bringing the first row of receptacles or 30 containers a underneath the several unit measuring positions. During the presence of the tray, or a continuous series of trays, in passing through the machine, the roller and arm will be maintained raised and the feeding 35 operation will continue until the last tray has passed beyond the roller, whereupon the roller and arm will drop, rendering the device ineffective.

By such construction, the motor of the 40 machine may be continuously operated, providing for longer or shorter intermission periods, if desired, the machine immediately resuming its functions upon the introduction of another tray with its receptacles or 45 containers.

A feature of improvement in the present machine is in providing the annular sharp edge lip 17, avoiding accumulation or creepage of ice cream at the lower end of each 50 unit measuring cavity, as above described. The removability of the cylinder, its open construction providing for free circulation of heated air so as to maintain the apparatus at any desired temperature, together with 55 the removability of the cylinder for cleaning or inspection, are features of considerable advantage and value.

In Fig. 11, I show a modified construction 60 for actuation of the segmental gear 33. Instead of pitman 35 and driving connection with crank disk 36, as in Fig. 1, an adjacent cross shaft 53 is provided with a terminal crank disk 54, having a crank roller pin 55. The latter engages an elongated slot 56 of 65 crank arm 57 of segment gear 33, so that, as

wrist pin 55 rotates it will impart the desired reciprocating movement to segment gear 33 and with the desired corresponding semi-rotation to gear 38, wheel 42 and barrel 9 in the same manner as already described. 70

The machine, in respect of the features above described, is particularly adapted to the work of rapidly and continuously filling containers with measured amounts of ice cream. It is comparatively simple in construction, easily kept clean and in repair, and can be operated without skilled labor. It may be changed or varied in detail construction by the skilled mechanic, or modified as to size, dimensions, or otherwise to 80 adapt it to other substances or conditions, but all such changes are to be considered as within the scope of the following claims. 75

I claim as my invention:

1. The method of extracting and ejecting 85 a measured unit from a superimposed mass of plastic material consisting in withdrawing a portion of the mass by suction into a confined space, then shifting the withdrawn portion laterally for severance from the 90 mass, and then relocating the unit for release of suction and discharge by gravity.

2. The method of extracting and ejecting 95 a measured unit from a superimposed mass of plastic material consisting in withdrawing a portion of the mass by suction into a confined space with accompanying expansion thereof due to suction, then shifting the withdrawn portion laterally for severance from the mass in such expanded condition, 100 and then relocating the unit for release of suction and discharge by gravity.

3. The method of extracting, separating 105 and delivering a measured unit from a superimposed mass of plastic material consisting in withdrawing a uniform column portion of the mass by suction and accompanying expansion, then shearing it from the mass while re-locating the unit, and discharging the unit by gravitation simultaneously and in cooperation with the withdrawal of another similar portion while subject to the action of a temperature raising medium. 110

4. The method of extracting, separating 115 and delivering a measured unit from a superimposed mass of plastic material consisting in withdrawing a uniform column portion of the mass by suction with accompanying expansion, then shearing it from 120 the mass while re-locating the unit, and discharging the unit by gravitation simultaneously and in cooperation with the withdrawal of another similar portion while maintaining on the withdrawn and severed portions action of a surrounding confined temperature raising medium. 125

5. The method of extracting, separating 130 and delivering a measured unit from a superimposed mass of plastic material con-

- sisting in withdrawing a uniform column portion of the mass by suction of a gravitating element with accompanying expansion of the unit, then shearing the portion 5 from the mass and re-locating it whereby to assist in actuation of the gravitating element, and then discharging the sheared unit by gravitation and in cooperation with the withdrawal of another similar portion.
- 10 6. Means for extracting a measured unit from a superimposed mass of plastic material consisting of an upper reservoir, a lower cylindrical casing communicating therewith, a semi-rotatable drum having a middle 15 transverse plunger cavity in full open undiminished registering communication with the reservoir and with an opposite substantially similar discharge opening in the casing, a longitudinally movable spline-controlled plunger in the plunger cavity adapted to freely withdraw a unitary portion from the reservoir by gravitating suction and to simultaneously follow a previously formed unit during its ejection, and separable means for imparting a part rotation to the cylinder.
- 20 7. In combination, a stub shaft having a ratchet wheel, a rotatable pawl carrier having a pawl therefor, means for intermittently rotating the pawl carrier in opposite directions, and a fender device for engagement with the pawl to render it inoperative.
- 25 8. In combination, a stub shaft having a ratchet wheel, a rotatable pawl carrier having a pawl therefor, means for intermittently rotating the pawl carrier in opposite directions, and a key terminal for driving engagement with a unit forming cylinder, a ratchet wheel secured to the shaft, a rotatable pawl carrier on the shaft having a pawl therefor, means for intermittently rotating the pawl carrier in opposite directions, and a fender device for engagement with the pawl to render it inoperative.
- 30 40 9. In combination, a stub shaft having a ratchet wheel, a rotatable pawl carrier having a pawl therefor, means for intermittently rotating the pawl carrier in opposite directions, a swinging arm having a fender 45 for engagement with the pawl to hold it away from the ratchet wheel, and a lever arm therefor having a terminal for engagement by a moving body for elevation of the lever and movement of the fender away 50 from the pawl.
- 55 10. In a machine of the class described, the combination with a rotatable unit forming cylinder and its casing and a supporting trackway for a container tray, of a stub shaft having a ratchet wheel and a key terminal for connection with the cylinder, a pawl carrier freely mounted on the shaft having a pawl and a gear wheel, a reciprocable driving segment therefor, a bearing 60 65 for the shaft, a swinging arm having a
- fender for engagement with the pawl, and a rock shaft therefor having an arm provided with a terminal roller for engagement by the tray.
11. In combination with an open ended 70 cylindrical casing having oppositely arranged receiving and discharge openings, a rotatable unit forming cylinder having transverse annular walls providing unit forming cavities with surrounding air circulation spaces.
12. In combination with an open ended 75 cylindrical casing having oppositely arranged receiving and discharge openings, a rotatable unit forming cylinder having series of transverse annular walls providing series of unit forming cavities with completely surrounding air circulation spaces.
13. In combination with an open ended 80 cylindrical casing having oppositely arranged receiving and discharge openings, a rotatable unit forming cylinder having series of transverse annular walls providing series of unit forming cavities with completely surrounding air circulation spaces.
14. In combination with an open ended 85 cylindrical casing having oppositely arranged receiving and discharge openings, a rotatable unit forming cylinder having series of transverse annular walls providing series of unit forming cavities with completely surrounding air circulation spaces.
15. In combination with a cylindrical casing 90 communicating with a reservoir and having at one end a centrally arranged rotating stem, a cylindrical unit forming member within the casing in rotative connection with said stem.
16. In combination with a cylindrical casing 95 communicating with a reservoir and having at one end a centrally arranged rotating stem, a cylindrical unit forming member within the casing in rotative connection with said stem, and having a removable bearing member at its other end.
17. In combination with a cylindrical casing 100 communicating with a reservoir and having its opposite ends open to the atmosphere, a cylindrical unit forming member rotatably mounted in the casing, centering spindles for the unit member at each end, and a supporting hub member therefor at each end providing for air circulation inwardly and outwardly of the unit member.
18. In combination with an intermittently 105 operable rotatable spindle having a turning key terminal and means supporting the same centrally of a cylindrical casing, a unit 110
19. In combination with a cylindrical casing 115 communicating with a reservoir and having its opposite ends open to the atmosphere, a cylindrical unit forming member rotatably mounted in the casing, centering spindles for the unit member at each end, a supporting hub member therefor at each end providing for air circulation inwardly and outwardly of the unit member, one of said hub members being removable to provide for removal of the unit member.
20. In combination with an intermittently 120 operable rotatable spindle having a turning key terminal and means supporting the same centrally of a cylindrical casing, a unit 125

forming cylinder removably inserted within the casing and having a central terminal hub adapted to engage the key terminal in a predetermined position.

5 19. In combination with an intermittently operable rotatable spindle having a turning key terminal and means supporting the same centrally of a cylindrical casing, a unit forming cylinder removably inserted within

10 the casing and having a central terminal hub adapted to engage the key terminal in a predetermined position, a central hub and stud at its other end, a supporting and retaining hub member therefor, and a removable

15 securing ring therefor secured to the other end of the cylindrical casing.

20 20. In a machine of the class described having a cylindrical casing provided with an upper inlet opening and a lower outlet

25 opening, an annular tapering edge member surrounding the lower opening, beyond an immediately adjacent surrounding channel for the purpose set forth.

21. In a machine of the class described having a cylindrical casing provided with an upper inlet opening and a lower outlet opening, an annular tapering edge member

surrounding and depending below the lower opening, beyond an immediately adjacent surrounding channel, and inner annular shearing edges surrounding both openings; a rotatable barrel within the casing having a continuous transverse unit chamber extending therethrough and terminated by annular shearing edges adapted to conform to and register with said openings.

30 35 22. In a machine of the class described having a cylindrical casing provided with an upper inlet opening and a lower outlet opening, an annular tapering edge member surrounding and depending below the lower opening, beyond an immediately adjacent surrounding channel, and inner annular shearing edges surrounding both openings; a rotatable barrel within the casing having a continuous transverse unit chamber extending therethrough and terminated by annular shearing edges adapted to conform to and register with said openings, and means for rotating said barrel one half revolution with a corresponding rest period.

40 45 In testimony whereof I hereunto affix my signature.

CHRISTIAN N. BERGMANN.
